CLAIM

The ornamental design for a digital audio player as shown and described.

DESCRIPTION

1. Digital audio player
- 1.1 : Perspective
- 1.2 : Perspective
- 1.3 : Front
- 1.4 : Back
- 1.5 : Left
- 1.6 : Right
- 1.7 : Top
- 1.8 : Bottom

The broken lines in the drawings illustrate the portions of the design that form no part of the claim; the characteristic features of the design lie in the combination of the shape and pattern; FIG. 1.1 is a front, right side, top perspective view of the digital audio player showing a new design; FIG. 1.2 is a rear, left side, top perspective view thereof; FIG. 1.3 is a front view thereof; FIG. 1.4 is a rear view thereof; FIG. 1.5

(Continued)

is a left side view thereof; FIG. 1.6 is a right side view thereof; FIG. 1.7 is a top view thereof; and FIG. 1.8 is a bottom view thereof.

1 Claim, 8 Drawing Sheets
